(57) **CLAIM**

The ornamental design for a medical arm board, substantially as shown and described.

DESCRIPTION

FIG. 1 is a front perspective view of medical arm board in a state of use with a patient table according to a first embodiment of the invention;

FIG. 2 is a front, raised perspective view of the medical arm board according to FIG. 1;

FIG. 3 is a top plan view of the medical arm board according to FIG. 1;

FIG. 4 a bottom plan view of the medical arm board according to FIG. 1;

FIG. 5 is a front view of the medical arm board according to FIG. 1;

FIG. 6 is a right side view of the medical arm board according to FIG. 1;

FIG. 7 is a left side view of the medical arm board according to FIG. 1;

FIG. 8 is a rear view of the medical arm board according to FIG. 1;

FIG. 9 is a front perspective view of a medical arm board according to a second embodiment of the invention;

FIG. 10 is a top plan view of the medical arm board according to FIG. 9;

FIG. 11 a bottom plan view of the medical arm board according to FIG. 9;

FIG. 12 is a front view of the medical arm board according to FIG. 9;

FIG. 13 is a right side view of the medical arm board according to FIG. 9;

FIG. 14 is a left side view of the medical arm board according to FIG. 9;

FIG. 15 is a rear view of the medical arm board according to FIG. 9;

FIG. 16 is a front perspective view of a medical arm board according to a third embodiment of the invention;

FIG. 17 is a top plan view of the medical arm board according to FIG. 16;

FIG. 18 a bottom plan view of the medical arm board according to FIG. 16;

(Continued)

FIG. 19 is a front view of the medical arm board according to FIG. 16;

FIG. 20 is a right side view of the medical arm board according to FIG. 16;

FIG. 21 is a left, side view of the medical arm board according to FIG. 16; and,

FIG. 22 is a rear view of the medical arm board according to FIG. 16.

The broken lines in FIG. 1 depict environmental subject matter that forms no part of the claimed design. The broken lines in FIGS. 9-22 depict portions of the medical arm board that form no part of the claimed design.
